UNITED STATES PATENT OFFICE.

JOSEPH PAQUETTE, OF ST. LOUIS, MISSOURI.

RANDING-MACHINE.

SPECIFICATION forming part of Letters Patent No. 288,850, dated November 20, 1883.

Application filed September 26, 1883. (No model.)

To all whom it may concern:

Be it known that I, JOSEPH PAQUETTE, of the city of St. Louis, in the State of Missouri, have invented a certain new and useful Improvement in Randing-Machines, of which the following is a full, clear, and exact description, reference being had to the accompanying drawings, forming part of this specification, and in which—

- 10 Figure 1 is a side elevation. Fig. 2 is an end view of the cutter-head. Figs. 3 and 4 are transverse sections taken, respectively, on lines 3 3 and 4 4, Fig. 1. Fig. 5 is a longitudinal section taken on line 5 5, Fig. 3; and Fig. 15 6 is a section of a boot or shoe sole trimmed with my machine.

My invention relates to a machine for cutting the bevels on the upper outer edges of boot and shoe soles; and my invention consists 20 in features of novelty hereinafter fully described, and pointed out in the claims.

Referring to the drawings, A represents a shaft journaled in boxes B, supported on a suitable base, C. The shaft has a driving-pulley, D, and a loose pulley, D', and to one end of it is secured a cutter-head, H, carrying knives I, secured thereto by screws J, or other suitable means. The ends of the knives project beyond the inner face of the cutter-head, forming cutting-edges whose inner corners project farther from the head than their outer corners, so that they cut a bevel on the soles, as shown in Figs. 5 and 6. The knives can be adjusted to make their cutting ends 30 protrude farther from the head by set-screws L, working through the outer portion of the head, and jamming against the rear ends of the knives. (See Fig. 5.) As the sole is be-

ing cut, it is held up against the knives by a sliding adjustable collar, N, surrounding the 40 shaft, and made to turn therewith by a key or projection, O, on the shaft working in a slot, P, in the collar. The outer end of the collar has preferably a flange, N', which bears against the sole. A spiral spring, T, surrounding the collar, is employed to push the collar toward the head when not forced back, thus holding the sole against the cutters to be trimmed.

I claim as my invention—

1. In a randing-machine, the combination of the shaft properly supported in journal-boxes, cutter-head carrying inward-projecting knives, and adjustable sliding collar for holding the sole-edge against the cutting-edges 55 of the knives, substantially as set forth.

2. In a randing-machine, the combination of the shaft supported in suitable journal-boxes, cutter-head carrying adjustable knives having inwardly-projecting beveled cutting-edges, and 60 the sliding collar, substantially as set forth.

3. In a randing-machine, the combination of the shaft supported in journal-boxes, cutter-head carrying bevel-edged knives secured thereto and made adjustable by two sets of 65 screws, and the sliding collar provided with a flange and surrounding the shaft, with which it is made to turn by a projection on the shaft entering a slot in the collar, and being surrounded by a spring, substantially as and for 70 the purpose set forth.

JOSEPH PAQUETTE.

In presence of—

GEO. H. KNIGHT,
JOSEPH WAHLE.
